UNITED STATES PATENT OFFICE.

JOHN LISKA, OF OVID, MICHIGAN.

DESIGN FOR A FLY-CATCHER.

48,186.

Specification for Design.

Patented Nov. 23, 1915.

Application filed August 23, 1915. Serial No. 46,970. Term of patent 7 years.

To all whom it may concern:

Be it known that I, JOHN LISKA, a subject of the Emperor of Austria-Hungary, residing at Ovid, in the county of Clinton and State of Michigan, have invented a new, original, and ornamental Design for a Fly-Catcher, of which the following is a specification, reference being had to the accompanying drawing, forming a part thereof.

The figure is a perspective view of a fly catcher showing my new design.

I claim:

The ornamental design for a fly catcher as shown.

JOHN LISKA.

Witnesses:

PAUL M. JARVIS,
W. J. MARTIN.
